LASTING MACHINE

Joseph W. Barna, Chicago, Ill., assignor, by direct and mesne assignments, of forty-nine one-hundredths to C. A. Laystrom, thirty-two one-hundredths to Mary Theresa Barna, five one-hundredths to Carl A. Laystrom, and fourteen one-hundredths to Valentine E. Hoffman, all of Chicago, Ill.

Application April 30, 1942, Serial No. 441,083

9 Claims.

(Cl. 12—7)

The invention relates to lasting machines of the type disclosed in my Patent No. 2,144,582, dated January 17, 1939, the general object of the invention being to simplify and improve the construction and arrangement to adapt it more particularly for the lasting of shoes having high uppers, as for example children's shoes.

An important object of the invention is to locate below one side of the wiper assembly the threaded shaft by which the wiper blade supporting slider blocks are shifted longitudinally of the machine, so that the shaft will not be in the way of a long upper extending down through the machine from a last to which the upper is being wiped.

A further object is to provide improved and simplified structure for holding the heel of the upper during wiping thereof.

Another object is to provide an improved last jack structure and adjustment therefor.

The various features of my invention are embodied in the structure shown on the drawings in which—

Figure 1 is a plan view of the machine with the wiper assembly removed;

Figure 2 is a plan view showing the wiper assembly;

Figure 3 is a section on plane III—III of Fig. 2;

Figure 4 is a section on plane IV—IV of Fig. 3;

Figure 5 is a section on plane V—V of Fig. 1;

Figure 6 is a section on plane VI—VI of Fig. 1;

Figure 7 is a front elevation to reduced scale showing particularly the treadle mechanism for operating toggle structure; and

Figure 8 is a plan view of the treadle mechanism.

The machine shown comprises a supporting frame F on which is mounted the base or bed structure B for supporting the various operating parts. The structure B comprises longitudinally extending side walls 10 and 11, a bottom wall 12, and walls 13 and 14 extending laterally from the upper ends of the side walls. The bottom wall 12 has the opening 15 therethrough which is in alignment with the opening 16 through the top of the supporting frame F.

Extending upwardly from the front end of the base bottom wall 12 is a pair of uprights 17 and 18 and at the rear end of the base is a similar pair of uprights 17' and 18'. The uprights 17 and 17' support a guide bar 19 while the uprights 18 and 18' support the guide bar 20. Receiving these bars are the front slider block 21 and the rear slider block 22 for movement on the bar toward and away from each other longi-

tudinally of the machine. The screw shaft 23 for the slider blocks is journaled in the uprights 18 and 18' below the guide bar 20. The front block 21 is bored to receive a bushing 24 internally threaded to receive the right hand threads on the front end of the shaft 23. The rear slider block has a similar bushing 24' receiving the left hand threaded rear end of the shaft 23. An arm 25 extends upwardly from the front end of the bushing 24 and is secured at its end, as by a screw 26, to the block 21 at the middle thereof. A similar arm 27 extends from the rear end of the bushing 24' in the rear block 22 and is secured by a screw 26' to the rear side of block 22 at the middle thereof. With this arrangement, upon turning of the hand wheel 28 at the front end of the shaft 23, the blocks will be moved toward or away from each other, the engagement between the ends of the arms 25 and 27 and the blocks at the middle thereof causing the blocks to shift easily along the guide bars 19 and 20.

The front block 21 has a dovetail channel 29 for receiving in its end the dovetail bottoms of posts 30 and 30' which are bored for receiving supporting pins 31. Each post has an arm 32 extending therefrom which at its outer end carries a supporting pin 33. Detachably secured by screws 34 to the pins 31 and 33 on the post 30 is the left toe wiper plate 35, the right toe wiper plate 36 being secured by screws 37 to the pins on the posts 30'.

The rear slider block 22 has the dovetail channels 38 at its ends for receiving the dovetail bottoms of the posts 39 to 39' each supporting at its upper end a pin 40 and having an arm 41 extending therefrom for support of a pin 42. Secured by screws 43 to the pins 40 and 42 is the left heel wiper plate 44, and by screws 45 the right heel wiper 46 is secured to the pins of the post 39'.

The side wipers 47 and 48 are supported, and associated with the toe and heel wipers, in the same manner as fully disclosed in my copending application Serial No. 437,331, filed April 6, 1942. Each side wiper is mounted on a slide bar 49 mounted in the guide head 50 at the upper end of a post 51 extending up from the machine base, the side wipers being rigidly secured to the inner ends of the bars 49 so as to be able to move only in one direction, namely widthwise of the machine. Each side wiper has channels 52 and 53 in its upper side receiving tongues 54 and 55 on the toe and heel wipers respectively so that as the toe and heel wipers are shifted longitudi-

nally and transversely of the machine the side wipers will be moved therewith widthwise of the machine. Mounted on the front slider block 21 between the posts 30 and 30' is the toe supporting bracket 56 (Fig. 3).

Mounted on the laterally extending walls or shelves 13 and 14 on the base B are the tables 57, 57' respectively, the tables having tongues 53 engaging in guide channels 59 in the supporting walls for guidance of the tables transversely of the machine. Toggle mechanism is shown for shifting the tables 57, 57'. Each table has a lug 60 extending downwardly therefrom through an opening 60' in the corresponding supporting wall, and depending from each supporting wall is a lug 61. Toggle links 62 and 63 fulcrum at their ends in the lugs 60 and 61, their inner ends being pivoted to a bar 64. The lower ends of the bars are connected by a cross bar 65 from the center of which a rod 66 depends and is guided in the head of a stirrup structure 67 which is suspended by its legs 67' which are secured to the base structure B, as best shown on Fig. 4. The lower end of the rod 66 is connected with treadle mechanism as shown on Figs. 7 and 8. The rod 66 is connected by a turn-buckle 68 with one end of a rocking lever 69 fulcrumed on a post 70 extending upwardly on a frame 71. The right end of the lever 69 is connected by an adjustable link 72 with a treadle lever 73 fulcrumed at its rear end to the frame 71, the treadle lever at its forward end being guided between vertical walls 74 extending upwardly from the frame 71. The left end of the lever 69 is connected by an adjustable link 75 with the treadle lever 76 fulcrumed at its rear end to the frame 71 and guided at its forward end by the wall 77 on the frame 71. Depression of the treadle lever 73 will effect downward pull of the rod 66 and operation of the toggles to shift the tables 57 and 57' outwardly, while depression of the treadle 76 will effect operation of the toggles to shift the tables inwardly.

On each of the tables 57, 57' are mounted front and rear cam rails 78 and 79, the rails being secured to the inner ends of bars 80 and 81 which are guided in channels 82 and 83 extending transversely of the respective table. Extending from the wiper supporting post 30 is an arm 84 having cam rollers 85 for engaging with the opposite sides of the cam rail 78 on the table 57. The post 30' has a similar arm 84 and rollers 85 engaging with opposite sides of the cam rail 78 on the table 57'. The rear cam rail 79 on the table 57 is engaged by the rollers 86 on the arm 87 extending from the post 39, and the cam rail 79 on the table 57' is engaged by rollers 86 on the arm 87 extending from the post 39'. The cam rails are similarly inclined so that when the slider blocks are shifted longitudinally of the machine by turning of the hand wheel 28, the toe wipers and the heel wipers will be moved transversely of the machine for closure of the wiper assembly against an upper to be lasted.

Each of the cam rail supporting bars has at its outer end a tongue 88 and a channel 89 inwardly of the tongue, the tongue and channel extending across the bar on the bias. Each of the bars is engaged by a gauge plate. The bars 80 of the cam rails 78 each engage with a gauge plate 90, while the bars 81 of the cam rails 79 engage each with a similar gauge plate 91. Each gauge plate has a groove 92 and a tongue 93 receiving respectively the tongue and groove on the corresponding rail supporting bar, the tongue and

groove of each gauge plate being inclined to the same angle as the tongue and groove in the corresponding bar. Each gauge plate has a rectangular head 94, the heads of the gauge plates 5 on the table 57 engaging in a rectangular guideway 95 formed in the table and extending longitudinally along the outer edge thereof, while the heads of the gauge plates on the table 57' engage in a guideway 94' formed longitudinally 10 along the outer edge of the table. A setting screw 96 extends through each guideway and has threaded engagement with the gauge plate heads in such guideway, each screw at its rear end being anchored and journaled in the end wall 15 97 on the respective table. Each screw terminates in a hand wheel 98 whereby it may be turned. By turning of the screw, the gauge plates are shifted relative to the bars 80 and 81 for setting of the cam rails transversely of the machine for the various sizes of uppers to be lasted. The gauge plate has scale indications 99 thereon 20 cooperating with pointers or arrows x and y respectively on the bars 80 and 81 for determining the setting to be made of the plates for the 25 desired size upper. The camming angles on the plates 90 and 91 are the same so that when the plates are moved in either direction by turning of the screw 96, and to the distance of one of the 30 scale divisions on the plates, the bars 80 and 81 will be shifted correspondingly equal distances for setting of their cam rails for change in shoe length of say one third of an inch. Thus, when the machine is to be used for the lasting of uppers for different shoe lengths, adjustment can 35 be made accurately and quickly by turning of the wheels 98 and the screws 96 for setting of the gauge plates.

Describing now the last jack and heel supporting structure, the supporting frame 100 for this 40 structure is mounted on an extension or bracket 101 at the rear side of the rear slider block 22. Extending upwardly from the frame are the ears 102 between which operates the jack structure supporting lever 103 fulcrumed at its rear end 45 by a pin 104. Pivoted to and depending from the forward end of the lever is the L-shaped bar 105 to the lower end of which is pivoted the standing jack body 106 by a pin 107. The jack post 108 has threaded engagement in the upper 50 end of the body 106 for up or down adjustment for engaging in the last holes of lasts in the machine over which uppers are to be wiped. On Fig. 3 L indicates a last, and U an upper being wiped thereover. The bar 105 and the jack body 55 106 extend through the recess 109 provided in the rear slider block 22, the bar 105 being guided in a channel 110 in the block at the back of the recess.

For raising and lowering the jack structure for 60 vertical adjustment of the last, a cam bar 111 is slidable between the ears 102 below the lever 103 and has the cam end 112 engageable with the lever for vertical swing thereof when the cam bar is shifted longitudinally. For shifting 65 the cam bar, a threaded shaft 113 extends rearwardly therefrom through the rear end of the frame 100 and is engaged by a nut 114 which, when turned, will effect longitudinal movement of the screw shaft and the cam bar for swing of the lever 103 and corresponding vertical adjustment of the jack structure.

Secured to and extending upwardly from the 70 frame 100 is a bracket 115 terminating in a head 116 which is threaded to receive a screw 117. The screw is bored to receive and support the

stem 118 which at its forward end terminates in a head 119 pivoted between ears 120 extending rearwardly from the heel engaging plate or frame 121 of arcuate cross section. By turning the screw 117 the stem with the heel frame thereon may be shifted longitudinally for adjustment of the heel frame relative to an upper, and the heel frame has slight vertical swing on the end of the stem, which swing is resisted by a spring 122 inserted between the stem head and the back of the heel frame. The heel frame and its stem are also rotatable in the supporting screw 117. The heel frame may thus be accurately applied against the heel portion of an upper and owing to its various movements it will readily fit itself into proper position against the upper heel portion to hold this heel portion securely against the last for preventing slipping thereof during operation of the wiper blade assembly.

A spring 123 secured to the bar 105 presses against the lower end of the jack body 106 and tends to hold this body vertical but permits swing of the body so that the jack post 108 may readily enter the last hole. The hook-shape jack structure may be of any length, depending on the length of the upper to be lasted, the openings 15 and 16 in the base B and frame F affording ample clearance for the upper. The setting screw 23 for the wiper assembly supporting blocks 21 and 22 being at one side of the passageways 15 and 16 will not interfere with nor obstruct the uppers, the upper extending freely down between the slider block guide bars 19 and 20.

It will also be noted that the wiper blade supporting posts on the slider blocks are comparatively short to bring the wiper blades closer down toward the machine base B and to afford more rigid support for the wiper blades during a wiping operation.

I have shown a practical and efficient embodiment of the various features of my invention but I do not desire to be limited to the exact construction and arrangement and operation shown and described as changes and modifications may be made without departing from the scope of the invention.

I claim as my invention:

1. In a lasting machine of the class described, a supporting base structure having an opening therethrough, front and rear slider blocks mounted on said base for longitudinal movement toward and away from each other, a screw shaft journaled on said base structure at one side of said opening, connections between said screw shaft and said slider blocks adapted upon turning of said shaft to effect movement of said blocks toward and away from each other, wiper elements supported by said slider blocks, a hook-shaped last jack structure supported on said rear slider block at one end of said base structure opening, said jack structure being of a length to receive comparatively long uppers for extension thereof through said base structure opening.

2. In a lasting machine of the type described, a supporting base structure having a clearance opening therethrough for long uppers to be lasted, guide bars extending along the sides of said base above said opening, front and rear slider blocks mounted on said guide bars for longitudinal movement thereon, a screw shaft journaled on said base structure at one side of said opening and having connection with said slider blocks whereby upon turning thereof said

slider blocks will be moved toward and away from each other on said guide bars, a wiper assembly supported on said slider blocks, said rear slider block having a recess in its front side, and a hook-shaped last jack adjustably supported on said rear slider block and depending therefrom through said recess and into said clearance opening.

3. In a lasting machine of the type described, a supporting base structure having a clearance opening therein for long uppers to be lasted, guide bars on said base structure extending along the sides and above said opening, front and rear slider blocks on said guide bars, a screw shaft journaled in said base structure at one side of said opening and having connections with said slider blocks whereby turning of said shaft will effect movement of said blocks toward or away from each other on said guide bars, a hook-shaped last jack structure suspended from said rear slider block and terminating at its upper end in a last hole receiving post, wiper assembly supported on said slider blocks, said jack structure being of a depth to freely receive long uppers for extension through said base structure opening while the uppers are being lasted by the wiper assembly.

4. In a lasting machine, a supporting base structure, front and rear slider blocks movable on said base structure lengthwise of the machine, toe wiper elements movable on said front slider block transversely of the machine and heel wipers on said rear block movable transversely of the machine, side wipers movable with said toe and heel wipers, means controlling the movements of said slider blocks and wipers, a support on said front slider block for the toe of a last on which an upper is to be wiped, a supporting frame on said rear slider block, a lever fulcrumed at its rear end on said frame, a jack structure supported from the forward end of said lever and terminating at its upper end in a jack post for receiving the jack hole of a last, a cam member movable on said frame for engagement with said lever for effecting vertical adjustment thereof and of the jack structure, a screw shaft in said frame connected with said cam member, and a nut on said frame engaging said screw shaft and adapted when turned to effect the movement of said cam member for vertical adjustment of said lever.

5. In a lasting machine of the type described, a wiper assembly for wiping an upper over a last in the machine, a frame at the rear of the machine below the wiper assembly, a lever fulcrumed at its rear end on said frame, a hook-shaped jack structure suspended from the forward end of said lever and terminating in its upper end in a last supporting jack post, a cam member shiftable on said frame and having a cam projection cooperable with said lever for effecting vertical adjustment thereof and of the jack structure, means on said frame for controlling the shift of said cam member, a rotatable and longitudinally adjustable rod on said frame above said jack structure supporting lever, and a heel plate mounted on the end of said rod for engagement with the heel portion of an upper to be wiped.

6. In a lasting machine, a base structure, supporting blocks movable longitudinally on said base structure toward and from each other, toe wiper structures shiftable on one of said blocks transversely of the base structure and heel wiper

structures movable on said other block transversely of the base structure, cam rails on said base structure one for each of said heel and toe wiper structures, said cam rails functioning to cause transverse relative movement of the toe and heel wiper structures upon movement of said blocks toward or from each other, gauge plates on said base structure having camming connection with said cam rails, and means for shifting said gauge plates for functioning of the camming connections to set said cam rails relative to said wiper structures.

7. In a lasting machine, a base structure, front and rear blocks shiftable on said base structure toward and from each other longitudinally of the machine, left and right toe wiper elements mounted on said front block for shift thereon transversely of said base structure and left and right heel wiper elements on said rear block shiftable thereon transversely of said base structure, left and right supporting tables on opposite sides of said base structure, cam rails on the left table engaged by the left toe and heel wiper elements and adjustable transversely of said base structure, cam rails on the right table engaged by the right toe and heel wiper elements and adjustable transversely of said base structure, said cam rails functioning to effect the transverse movement of said toe and heel wiper elements when said blocks are moved toward or from each other, gauge plates shiftable longitudinally on each of said tables and having camming connections with the corresponding cam rails, and means on each table for shifting the gauge plates predetermined distances for corresponding transverse movement and setting of said cam rails and wiper elements.

8. In a lasting machine, a pair of toe wipers movable toward and from each other trans-

versely of the machine, a pair of heel wipers movable toward and from each other transversely of the machine, said toe wipers and heel wipers being movable toward and from each other 5 lengthwise of the machine, a cam member for each wiper element and abutments on said element engaging said cam member, said cam members being adjustable transversely of the machine for setting of said wiper elements for the 10 desired size of shoe uppers to be lasted, gauge elements shiftable longitudinally of the machine, connection between said gauge elements and the respective cam elements effective upon predetermined longitudinal movement of said gauge members to set said cam elements and the corresponding wiper elements transversely of the machine, and means in the form of screw shafts for 15 effecting the adjustment of said gauge elements.

9. In a lasting machine, a base, supporting 20 blocks movable longitudinally on said base structure toward and from each other, toe wiper structures shiftable on one of said blocks transversely of the base and heel wiper structures shiftable on said other block transversely of the 25 base, individual cam rails on said base for said toe and heel wiper structures and engaged thereby, said cam rails functioning to cause transverse relative movement of the toe and heel wiper structures upon movement of said blocks toward 30 or from each other, a pair of gauge plates at each side of said base having camming connections with the cam rails of the respective toe and heel wipers, and a screw shaft for each pair of gauge plates for simultaneous shifting thereof 35 for functioning of said camming connections to adjust the respective cam rails and wiper structures transversely of the base.

JOSEPH W. BARNA.
